WELL CLEANING DEVICE

Landes H. Hayward, Long Beach, Calif., assignor,
by mesne assignments, to McGaffey-Taylor
Corporation, Bakersfield and Long Beach, Calif.,
a corporation of California

Application November 20, 1935, Serial No. 50,675

27 Claims. (Cl. 166—26)

This invention relates generally to well cleaning devices and particularly to devices for scavenging or cleaning the perforations in the strainer casing of an oil well, whereby to revive or enhance its flow.

To those familiar with the art of petroleum production, it is known that an oil well contains an imperforate casing which extends down to the oil producing sand or zone. It is attached to a strainer casing having therein slots or perforations through which the oil seeps, or is forced from the oil bearing zone by the rock pressure. The perforations in the strainer casing become clogged with debris, sand, tar, paraffin, and the like, which retards the flow of the oil into the casing, thus reducing the production of the well.

Furthermore, channels are formed in the formation adjacent the perforated casing due to the continuous passage of gas and oil therefrom into the casing. When the natural gas pressure of the well begins to diminish, these channels also become clogged with sand, tar, and the like, which retards the flow of oil into the perforated casing. It is the contemplation of this invention to open these channels and also the clogged perforations in the casing in order to enhance or revive the flow of the well.

Various types of apparatus are used for performing this cleaning operation. Some comprise spaced packing devices which may be lowered into the perforated casing to any designated zone and which are cooperative with the casing to form a confined chamber from which fluid is forced through the perforations of the strainer casing. Various methods are employed for forcing fluid from this chamber through the perforations of the packed off area of the strainer casing. This is sometimes accomplished by stationarily supporting one packing device within the perforated casing and moving the other of said packing members relative thereto for displacing the liquid therebetween. Another method commonly employed is to stationarily support a pair of relatively fixed packing devices within the well casing and force fluid therefrom through the casing perforations in any one of a number of ways, all of which are well known to those familiar with the art. In any event the maximum distance between the packing members must be kept small to permit the building up of a pressure within the confined chamber sufficiently great to "break" the perforations in the strainer casing. Accordingly, a great number of settings of the packing members is required to clean the entire length of casing. The perforated

casing is sometimes a number of hundred feet in length and the time required to clean the same is an essential, since the well production is shut down during the cleaning operation.

It is accordingly one of the objects of this invention to provide a well cleaning device by which a greater length of perforated casing or strainer may be cleaned at each setting thereof than has heretofore been possible.

Another object of the invention is the provision of packing means which is cooperative with the interior of a perforated well casing for defining a chamber therein, with means for moving said chamber and simultaneously applying a fluid pressure thereto during the course of its movement.

A further object of the invention is the provision of a well washing device comprising means forming a chamber within a perforated casing or the like, with means for reciprocating said chamber within the casing and further means acting on said chamber for alternately increasing and decreasing the fluid pressure therein relative to the fluid pressure externally of said casing, whereby to cause the flow of fluid back and forth through the perforations of said casing during the reciprocation of said chamber.

Another object of the invention is the provision of a device which may be readily moved to any position within a perforated pipe in a well, and which includes a pair of spaced packing devices which are cooperative with said perforated pipe and adapted to be reciprocated therein as fluid pressure is applied therebetween from within the device, for forcing fluid outwardly through the perforations to effect a cleaning thereof.

Another object of the invention is the provision of means within the device itself, for applying a fluid pressure between the packing devices as they are moved in one direction for forcing fluid outwardly therefrom through the perforations, and to lower the pressure between said packing devices during their movement in the opposite direction to set up a differential pressure into the space therebetween, thereby facilitating the cleaning of the perforations through the movement of fluid therethrough in the opposite direction.

Another object of the invention is the provision of a device which is adapted to be positioned within the perforated casing of a well and which includes relatively fixed packing devices which are cooperative with the interior of said casing and adapted to be moved relative thereto, as pressure is applied from within the

device to the space between said packing devices, whereby to force fluid through the casing perforations.

A further object of the invention is to provide a device of the character referred to which is simple of construction and which is positive in its operation to effect the purpose for which it is designed.

This invention possesses many other advantages and has other objects which may be made more easily apparent from a consideration of the embodiment thereof shown in the accompanying drawing and forming part of the present specification. I shall now proceed to describe this form in detail, which illustrates the general principles of my invention; but it is to be understood that this description is not to be taken in a limiting sense, since the scope of my invention is best defined in the appended claims.

20 In the drawing:

Figure 1 is a longitudinal sectional view through a perforated casing showing the lower portion of my well washing apparatus supported therein.

25 Figure 2 is a longitudinal sectional view through the perforated casing showing the upper portion of my device suspended therein.

Figure 3 is a transverse sectional view taken as indicated by line 3—3 of Figure 1.

30 Figure 4 is a transverse sectional view taken as indicated by line 4—4 of Figure 1.

Figure 5 is a transverse sectional view taken as indicated by line 5—5 of Figure 1.

35 Figure 6 illustrates a modified form of by-pass construction contemplated by my invention, and

Figure 7 is a transverse sectional view through said by-pass construction and taken as indicated by line 7—7 of Figure 6.

40 The well cleaning device contemplated by my invention is shown within a strainer casing 10 such as is commonly employed in oil wells opposite the oil producing zone. It is the practice to connect said perforated casing with a string of imperforate casing (not shown) which extends to the top of the well and through which the oil is pumped to the surface. In general, my device includes upper and lower sections A and B respectively. The upper section A is connected to the end of a string of tubing 11, by which the device is lowered as a whole into the well, and operated to effect a scavenging or cleaning of the perforations 12 in the casing 10, whereby to revive the flow of oil from the well.

45 The upper section A (Figure 2) includes a hollow tubular member 13 which carries thereon a pair of relatively fixed packing members 14 and 15 of any suitable conventional type, and which define a space P therebetween. Although any suitable packing means might be employed, I 50 prefer to use cup shaped packers constructed from rubber or other suitable material and which are commonly known as swab cups. These packers are held against unlimited outward movement by a plurality of retaining wires 16 and 17 55 which are embedded in the sides of said packers and have their outer ends secured in guide rings 18 and 19. The upper swab cup 14 enters the lower cupped portion of a clamping member 20 and is invertedly supported between a shouldered portion 21 of said clamping member and a shoulder 22 welded or otherwise secured to the hollow tubular member 13. The clamping member 20 is also provided with an upper cupped portion which receives another swab cup 23 supported therein 60 in an upright position. It is similar in construc-

tion to the swab cups 14 and 15 and carries retaining wires 24 whose outer ends are secured in a guide ring 25. The swab cups 14 and 23, together with the intermediate cupped member 20, are all clamped between the shoulder 22 and the 5 lower end of a coupling 26 which is threaded onto the upper end of the hollow tubular member 13 and serves to connect said tubular member with the lower end of the tubing string 11.

The lower swab cup 15 is supported in an upright position relative to the upper inverted swab cup 14. It enters a thimble 27 and is clamped between said thimble and a fixed shoulder 28 on the hollow tubular member 13 as by a nut 29 on the threaded end 30 of the hollow tubular 15 member. The threaded end of said tubular member enters a coupling 31 which is in turn threaded into a cylinder 32. The cylinder slidably telescopes over a plunger 33 carried on the upper end of section B, thus forming a fluid pressure 20 chamber O. Communication between the chamber O and the space P between the relatively fixed packers 14 and 15, is established through the hollow tubular member 13 and openings 34 leading therefrom into the space between the packers 25 14 and 15. Thus, it will be obvious how I have established a fluid passage between the outer wall and the fluid chamber O, through the casing perforations 12, space P, passages 34 and the hollow tubular member 13. It will also be 30 obvious how I have provided means for alternately increasing and decreasing the fluid pressure within the space P relative to the exterior hydrostatic pressure of the well, upon reciprocating section A relative to section B, thus creating 35 a swashing of fluid back and forth through the casing perforations. During the cleaning operation section B with its plunger 33 is stationarily supported within the perforated casing 10 by a slip mechanism generally designated H and hereinafter fully described.

The reciprocating action of the section A may be accomplished by attaching the string of tubing 11 to the blocks and coupling mechanism usually found on the derrick structure. In the 45 drawing, section A is shown at the upper end of its stroke at which time chamber O, tubular member 13 and space P would all be filled with fluid. The weight of said tubing string is effectively utilized to operate section B on its downward stroke, to displace the fluid from chamber O and tubular member 13 through the passages 34, thus building up a pressure in the space P in excess of the hydrostatic pressure of the well. It will be obvious how fluid will accordingly be 55 forced from the space P outwardly through the perforations, during the course of its downward movement.

The lower end of the perforated casing often 60 experiences the greatest clogging effect, and an excessive pressure is sometimes required to break through the perforations in this region. In my well washing apparatus it will be obvious how the pressure within the chamber O is increased during the downward movement of section A and the fluid pressure in the space P correspondingly increased, until the pressure therein is greatest at the lower end of its travel where it is needed the most when operating in the lower portion of the perforated casing. The washing 65 operation is further enhanced during the upward movement of the section A. When moved in this direction the internal pressure is correspondingly reduced as the area of the fluid chamber O is increased, whereby the external hydro- 70 pressure is reduced. 75

static pressure in the well forces fluid from the well back through the perforations into the space P, through the tubular member 13 and into the fluid chamber O. Thus, it will be seen that the fluid is forced back and forth through the perforated casing confined by the movable packing members 14 and 15 as said packers are reciprocated with section A, resulting in an effective swashing effect for scavenging the perforations.

In practice, the device is usually first lowered to the lower end of the perforated casing and the section A given one or more strokes of the character heretofore described. In order to further enhance the effectiveness of the washing operation at the lower end of the perforated casing where the perforations are usually clogged the greatest, I provide a packing member 34a on the lower end of cylinder 32, and below the plunger 33 (Figure 1). I prefer to use a packing member similar in construction to the packing members 14 and 15, which are shown as being in the form of annular swab cups made from suitable resilient material as heretofore explained. This swab cup 34a is invertedly supported in an annular seat formed in a clutch member 35, which is in turn screw threaded into the lower end of the cylinder 32. Said swab cup is held in said seat by a shouldered sleeve 36 which is threaded into the clutch member 35. Similarly to the packing cups 14 and 15, the packing cup 34a is held against unlimited outward movement by retaining wires 37, which are embedded in its sides and have their outer ends secured in a guide ring 38. The operator knowing the length of stroke of section A can accurately control its movement relative to section B. However, in order to insure against the inadvertent engagement of the plunger 33 by the member 31, I provide a cushioning spring 39 within the upper end of the cylinder 32. Said spring may be welded or otherwise adequately secured to the member 31 as clearly shown in Figure 2.

As has heretofore been described, section B carries the plunger 33 and anchor means H for stationarily supporting it within the perforated casing, as section A is reciprocated relative thereto for effecting the washing operation. The section B includes upper and lower hollow tubular members 41 and 42 respectively, which are interconnected by a hollow coupling member 43 to form the fluid passage D. A guide head in the form of a coupling 55 is threaded onto the lower end of the tubular member 41 and facilitates in guiding the apparatus through the perforated casing. It is provided with fluid passages 55a. The coupling 43 serves as a slip head for the anchor means H and is provided with tapered faces 44 which slidably receive slips 45. The slips are connected through toggle links 46 to a collar 47 on the upper end of a slip control sleeve 48, which is slidable on the lower tubular member 42. Said collar surrounds the upper end of said sleeve and is rotatably supported thereon between a shoulder 49 and nut 50 threaded onto the upper end of the sleeve. The slip control sleeve 48 carries a plurality of spring elements 51 which are adapted to frictionally engage the interior of the perforated casing 10. It also carries a bayonet slot 52 which slides over a pin 53 extending from the hollow tubular member 42. A dovetail connection (not shown) may be provided between the slips and the head 43 to insure their engagement with the tapered surfaces at all times. The bayonet slot and pin arrange-

ment is such, that when the pin is in the offset portion of the bayonet slot, the slips are positively held in a retracted position away from the perforated casing and the tubular member 42 of section B is restrained against movement through the slip control sleeve 48. This locked position of the slips in their retracted position is maintained during the movement of the apparatus into and out of the well, thus insuring against their inadvertent engagement with the well casing. When it is desired to "set" the apparatus for operation, a rotative movement is imparted to section B until the pin 53 registers with the longitudinal portion of the bayonet slot 52. Section B is then free to move downwardly relative to the slip control sleeve 48 which is stationarily supported by the frictional engagement of the spring members 51 with the casing 10. It will thus be obvious how the slips will be forced outwardly by the slip head 43 until they engage the interior of the casing 10 at which time they become effective to stationarily support the entire section B with its plunger 33.

The means for rotating section B to lock and unlock the slip mechanism, comprises clutch means between sections A and B, whereby the operator can, upon rotating the string of tubing 11, impart a rotative movement to section B. This clutch means is in the form of two pairs of diametrically opposed arcuate lugs 19a and 20a, which extend from the plunger 33 and clutch member 35 respectively. Figures 4 and 5 show the relative position of the opposing pair of lugs just before engagement, which is accomplished by raising section A until the lugs 20a of the clutch member 35 enter the spaces between the lugs 19a, at which time sections A and B may be rotated as a unit.

In order to insure a tight seal between the plunger 33 and telescoping cylinder 32, I provide passages 56 which are communicative between the fluid pressure chamber O, and the joint formed between the piston body 57 and the yieldable packing ring 58. Said packing ring is held between an annular shoulder 59 formed on the lower end of the plunger, and a retaining nut 60 threaded onto the upper end of the piston body. The nut 60 is secured in place by a lock nut 61. When the cylinder 32 is moved downwardly it will be obvious how fluid will be forced through the passages 56 and behind the packing ring, thus urging it against the interior of said cylinder to insure a tight seal therewith.

In order to facilitate the movement of the apparatus into and out of a fluid filled well casing, a by-pass structure is provided in the plunger 33 for the passage of fluid. The piston body 57 is threaded onto the upper end of the hollow tubular member 41 and has an opening 62 therethrough which forms a continuation of the passage D in said tube. A member 63 is threaded into the upper end of the opening 62 and is provided with a valve seat 64 for receiving the head 65 of a valve. The valve stem 66 extends downwardly through the piston opening 62 and carries a cross arm 67 which extends through diametrically opposed guide slots 68 formed in the hollow tubular member 41. A spring 69 interposed between the member 63 and cross arm 67 serves to normally hold the valve head in seated position.

The ends of the cross arm extend beyond the outer periphery of the tube 41, into the spaces between the clutch lugs 19a depending from the bottom of the piston (Figures 1 and 4). Said arm is disposed considerably above the bottom

faces of said clutch members as shown clearest in Figure 1. In removing the apparatus from the well, section A is lifted upwardly until the lugs 20a on the clutch member 35 enter the spaces 5 between the lugs 19a and engage the cross arm 67, thereby lifting the valve head 65 from its seat and permitting the free flow of fluid through the plunger as the apparatus is withdrawn from the well casing. Upon lowering the apparatus 10 into the casing the combined resistance of the fluid and the frictional resistance of the springs 51 with the casing, tend to keep the plunger 33 well up into the cylinder 32 and away from the clutch member 35. During this downward 15 movement, the fluid is free to pass upwardly through the passage 70 of the valve stem. The ball valve 71 is of course raised from its seat, thus permitting fluid to enter the chamber O and pass upwardly through the hollow tubular member 13.

In order to build up the necessary pressure within the chamber O and tube 13 during the operation of the working cylinder, it is essential to provide closure means within the passage 25 leading to the tubing string 11 and above the openings 34 leading into the space S between the packers 14 and 15. It is also necessary that means be provided for permitting the free passage of fluid through the closure, upon lowering 30 the apparatus into, and raising it from the well. I accomplish the above necessities through a by-pass structure which is normally maintained in an open position during the movement of the apparatus into the well, but which is closed prior 35 to the cleaning operation, as by dropping an element down the tubing string, which supports the apparatus within the well. Upon raising the apparatus from the well, the by-pass structure is acted upon by fluid pressure to effect an opening 40 thereof for permitting the passage of fluid through the cleaning apparatus.

The by-pass structure is embodied within the coupling 26 which connects the tubing string 11 with the tubular member 13 of the cleaning apparatus. It includes a cylindrical member 72 which is supported on an internal shoulder 73 of the coupling 26. The bottom of said cylindrical member is provided with a threaded opening to receive a member 74 having a valve seat 75 formed therein. A valve 76 is provided with a stem 77 which extends through an enlarged opening 78 in the member 74 and carries on its upper end a disc 79 having a series of peripheral openings 79' therein for the passage of fluid. The disc slidably engages the internal wall of the cylinder 72 and carries an upwardly extending portion 80 which has a chamber 81 formed therein. Said portion is externally threaded to receive a threaded cap 82, which serves to clamp 50 a frangible disc 83 against the upper end of the member 80. The valve 76 is normally held open by the engagement of the frangible disc with a plunger pin 84, which is carried by a plunger member 85 slidably mounted in a plate 86 carried on the upper end of the cylindrical member 72. A spring 87 urges the frangible disc against the plunger pin 84, which together with its supporting member 85, is restrained against upward movement by the engagement of a shoulder 88 on the member 85 with the plate 86. The plate 86 is supported on the upper end of the cylindrical member 72 and is provided with a number of openings 89 for the passage of fluid. Said plate is stationarily held between the upper 75 end of the member 72 and a ring 90, against

which the lower end of the tubing string 11 is threaded.

As the apparatus is lowered into a fluid filled well casing, the fluid is free to pass upwardly through the passage D, lifting the ball valve 71 upon entering the chamber O. The fluid is free to continue upwardly through the tubular member 13 and through the by-pass construction, which is maintained in the open position shown in Figure 2. Passages 91 are provided in the tubing string 11, above the by-pass construction, to permit the flow of fluid into the well casing. Upon reaching the desired location within the well, the slip mechanism may be set in a manner heretofore described, for stationarily supporting the plunger 33 within the casing. The valve 76 of the by-pass mechanism may then be closed as by dropping an element down the tubing string 11. Said element is adapted to strike the head 92 of the plunger member 85, whereupon the plunger pin 84 breaks the frangible disc, the pieces of which fall into the chamber 81 formed in the member 80. Upon breaking the frangible disc, the spring 87 forces the valve 76 to closed position. It will be obvious how a closed chamber is established within the apparatus, the only openings therein being the passages 34 leading from the tubular member 13 into the confined space or chamber P defined by the spaced packing members 14 and 15, thus making possible the establishment of a tremendous pressure within said closed chamber upon moving the section A downwardly over the stationarily supported plunger 33. It will also be obvious how a fluid pressure is correspondingly applied to the space 30 P during its movement along the perforated casing, thus forcing fluid outwardly through the perforations to effect a scavenging thereof. Upon moving section A upwardly, the area within the closed chamber is increased and a fluid 35 pressure differential is produced back through the perforations, through the confined space P, and into the closed chamber, whereby to enhance the cleaning of the perforated casing 40 length traversed by the space P.

The fluid pressure within the chamber or space P is progressively increased during the displacement of fluid from the closed pressure chamber upon downward movement of the section A, thus insuring a thorough cleaning of the perforations at the bottom of the stroke. It will accordingly be unnecessary to provide for an overlapping of the washing stroke upon each setting of the device, thus facilitating in a cleaning of the entire length of perforated casing in a minimum of time.

When it is desired to move the apparatus within the casing, the anchor means H may be released in a manner heretofore fully described, by rotating and lifting the tubing string 11. An easy removal of the apparatus from the well is provided by establishing a free fluid passage downwardly through the apparatus as heretofore described. Upon upward movement of the apparatus, the uppermost packing member 23 forces fluid through the passages 91 of the tubing string 11, into the cylinder 72 of the by-pass structure, where the fluid pressure acts on the upper surfaces of the various parts to open the valve 76 and permit the free passage of fluid. The engagement of the clutch elements with the cross arm 67 maintains the valve 65 in open position during the upward movement, thus establishing a fluid passage through the plunger 33.

Figure 6 is a modified form of by-pass con-

struction, which for purposes of illustration is shown embodied in a coupling 93, used for connecting my apparatus with a string of tubing. It includes a cylindrical member 94 which is seated on an internal shoulder 95 of the coupling and carries a member 96 having a valve seat 97 formed therein. The stem 98 of a valve 99 extends through an enlarged opening in the member 96 and has an externally threaded portion 100 formed on its upper end which defines a chamber 101. A threaded cap 102 serves to retain a frangible disc 103 on the member 96, and the entire valve structure is normally held in an open position by the engagement of the 15 frangible disc with a plunger pin 104 formed on a plunger arm 105. The opposite ends of the plunger arm are contained in diametrically opposed slots 106 and 107 formed in the cylindrical member 94. The slot 107 is longer than the slot 106 and the plunger arm is urged against the upper end of the slot 107 by the spring 108 to assume the angular position shown in the drawing. However, upon being struck by an element dropped through the tubing string, it will be obvious how the plunger arm will swing downwardly to force the plunger pin through the frangible disc, whereupon the spring 108 forces the valve closed. Suitable openings (not shown) might be provided in the tubing string 109 for 20 permitting fluid pressure to act on the upper surfaces of the valve structure to open the same when removing the apparatus from a fluid filled well.

I claim:

35 1. In an apparatus for cleaning perforations in pipe and the like: means movable in said pipe and defining a confined space therein, means for moving said space defining means, and means including a cooperative cylinder and plunger 40 within said pipe but outside of said confined space for applying pressure to said confined space during the movement of said space defining means.

2. In an apparatus for cleaning perforations 45 in pipe and the like: packing means movable in said pipe and defining a confined space therein, means for moving said packing means, and means including a cooperative cylinder and plunger within said perforated casing but outside 50 of said confined space for applying pressure to said confined space during the movement of said packing means.

3. In an apparatus for cleaning perforations 55 in pipe and the like: packing means movable in said pipe and defining a confined space therein, means for moving said packing means, and means interiorly of said perforated pipe but outside of said confined space for producing a movement of fluid to and from said confined space 60 through the perforations of said pipe during the movement of said packing means.

4. In an apparatus for cleaning perforated 65 pipe and the like: a pair of relatively fixed spaced packing members adapted to engage the interior of said pipe and to form a confined space therein; means for movably supporting said packing members within said pipe; a cylinder, means for supporting the cylinder for movement with said packing members, said cylinder having communication with said confined space; a plunger cooperative within said cylinder and adapted to be stationarily supported within said pipe, means for stationarily supporting said plunger with respect to said cylinder; and means for actuating 70

said packing members and cylinder with respect to said plunger for forcing a pressure fluid into said confined space as said packing members are moved within the perforated pipe.

5. In an apparatus for cleaning perforated 5 pipe and the like; a pair of relatively fixed spaced packing members adapted to engage the interior of said pipe and to be moved relative thereto; means for supporting said packing members; a cylinder, means for supporting the cylinder for 10 movement with said packing members, said cylinder having communication with the space therebetween through said supporting means; a plunger, and means for stationarily supporting said plunger with respect to said cylinder, said 15 plunger being cooperative with said cylinder for forcing a pressure fluid from said cylinder into the space between said packing members during their movement within the perforated pipe.

6. In an apparatus for cleaning perforated 20 pipe and the like: a pair of relatively fixed spaced packing members adapted to engage the interior of said pipe and to form a confined space therein; means for movably supporting said packing members; a cylinder, means for supporting the 25 cylinder for movement with said packing members, said cylinder communicating with said confined space; a plunger cooperative within the cylinder, and means for stationarily supporting said plunger within the perforated pipe as said 30 cylinder is moved downwardly relative thereto for forcing a pressure fluid into said confined space during the movement of said packing members.

7. In an apparatus for cleaning perforated 35 pipe and the like: a pair of relatively fixed spaced packing devices adapted to engage the interior of said pipe and to form a confined space therein; means for movably supporting said packing devices; a cylinder, means for supporting the 40 cylinder for movement with said packing devices, said cylinder communicating with said confined space; a plunger cooperative within the cylinder, and means for stationarily supporting said plunger within the perforated pipe as said 45 cylinder is reciprocated relative thereto for producing a movement of fluid to and from said confined space through the perforations of said pipe, during the movement of said packing devices.

8. In an apparatus for cleaning perforated 50 pipe and the like: a pair of relatively fixed spaced packing members adapted to engage the interior of said pipe and to form a confined space therein; a hollow member supporting said packing 55 members and having an opening leading into said confined space; a cylinder, means for supporting the cylinder for movement with said packing members, said cylinder being in communication with the confined space through said 60 hollow supporting member; a plunger in said cylinder; means for stationarily supporting said plunger with respect to said cylinder; and a string of hollow tubing for supporting and actuating said packing members and cylinder with 65 respect to said plunger.

9. In an apparatus for cleaning perforated 70 pipe and the like: a pair of relatively fixed spaced packing members adapted to engage the interior of said pipe and to form a confined space therein; means for movably supporting said packing members; means including a cooperative cylinder member and piston member within said 75 perforated pipe for applying fluid pressure to said confined space during the movement of said

packing means for supporting one of said cooperative members for movement with said packing members, and means for stationarily supporting the other of said members with respect to said first member.

10. An apparatus for cleaning perforated pipe and the like including: packing means adapted to engage the interior of said perforated pipe and to form a confined space therein; means for 10 movably supporting said packing means; means including a cooperative cylinder and piston within said perforated pipe for applying pressure fluid to said confined space during the movement of said packing means; and means forming a valve-controlled by-pass in one of said cooperating members.

11. An apparatus for cleaning perforated pipe and the like including: packing means adapted to engage the interior of said perforated pipe and to form a confined space therein; means for 20 movably supporting said packing means; means including a cooperative cylinder member and piston member within said perforated pipe for applying pressure fluid to said confined space 25 during the movement of said packing means; means forming a by-pass in one of said cooperating members; valve means associated with said by-pass, and means associated with the other of said cooperating members for actuating said 30 valve means.

12. In an apparatus for cleaning perforations in pipe and the like: a pair of relatively fixed spaced packing members adapted to engage the interior of said pipe and be moved relative thereto, means for movably supporting said packing members, a cylinder, means for supporting the cylinder for movement with said packing members, said cylinder being communicative with the space between said packing members, a plunger 40 cooperative within said cylinder, means for stationarily supporting the plunger in said pipe as said cylinder and packing members are moved relative thereto, said plunger having a passage therein, and valve means adapted to be actuated by means associated with said cylinder for rendering said passage communicative with said cylinder.

13. In an apparatus for cleaning perforated pipe and the like in a well, a pair of relatively 50 fixed spaced packing members adapted to engage the interior of said pipe and be moved relative thereto, means for movably supporting said packing members, a cylinder, means for supporting the cylinder for movement with said packing members, said cylinder being communicative with the space between the packing members, a plunger cooperative within said cylinder, means for stationarily supporting the plunger in said pipe as said cylinder and packing members are moved relative thereto, said plunger having a passage therethrough, valve means for said passage, and means for acting on said valve to maintain it in open position when the apparatus is moved bodily within the well.

65 14. In an apparatus for cleaning perforated pipe in a well, a pair of relatively fixed spaced packing members adapted to engage the interior of said pipe and be moved relative thereto, means for movably supporting said packing members, a cylinder, means for supporting the cylinder for movement with said packing members, said cylinder being communicative with the space between the packing members, a plunger cooperative within said cylinder, means for stationarily 70 supporting the plunger in said pipe as said cyl-

inder and packing members are moved relative thereto, said plunger having a pair of passages therethrough, separate valve means for each of said passages, one of said valves being actuated by fluid pressure to permit the passage of fluid through the plunger when the apparatus is moved in one direction within the well, and the other of said valves being actuated by means associated with said cylinder for permitting the passage of fluid through said plunger when the apparatus is moved in the opposite direction.

15. In an apparatus for cleaning perforated pipe and the like in a well, a plunger, means for releasably supporting said plunger within the perforated pipe, valve means associated with said plunger for permitting the free passage of fluid therethrough as the apparatus is raised and lowered within the well, a pair of relatively fixed packing members adapted to engage the interior of said pipe and form a confined space therein, a hollow member for movably supporting said packing members, said hollow member having an opening communicating with said confined space, a cylinder cooperative with said plunger, means for supporting the cylinder for movement with said packing members and with respect to said plunger for forcing a pressure fluid into said confined space during the movement of said packing members, and valve means in said hollow supporting member above the opening leading into said confined space, said valve being operable by dropping an element down the hollow supporting member.

16. In a device for circulating liquid through perforations in well casing, means defining a space in cooperation with the well casing, said means including a pair of relatively fixed members, means disposed within the well casing outside of said space defining means for alternately passing liquid from the space through the perforations, and then passing liquid from the perforations into said space, and means for moving said space defining means as liquid is passed to and from said space.

17. In a device for circulating liquid through 45 perforations in well casing, means defining a space in cooperation with the well casing, said means including a pair of relatively fixed members, means for moving said space defining means with respect to the casing, and means disposed 50 within the well casing outside of said space defining means for passing liquid from the space through the perforations during the movement of said space defining means.

18. In a device for circulating liquid through 55 perforations in well casing, means defining a space in cooperation with the well casing, said means including a pair of relatively fixed members, means for moving said space defining means with respect to the casing, and means operative within 60 the well but outside of said space defining means for effecting the passage of liquid from the perforations into said space during the movement of said space defining means.

19. In a device for circulating liquid through 65 perforations in well casing, means movable in the casing and defining a space in communication with some of said perforations, said means including a pair of spaced members in fixed relation to each other, means for moving said space 70 defining means with respect to the well casing, and means operative by the movement of said space defining means but outside of said space defining means for effecting the passage of liquid through the perforations traversed by said 75

space during the movement of said space defining means.

20. In a device for circulating liquid through perforations in well casing, means defining a space in cooperation with the well casing and in communication with some of said perforations, means for moving said space defining means, and pressure creating means for effecting the circulation of liquid from said space through the perforations during the movement of said space defining means, said pressure creating means including cooperative piston and cylinder elements, means for supporting one of said elements for movement with said space defining means, and means for stationarily supporting the other of said members. 10

21. In a device for circulating liquid through perforations in pipe and the like, means defining a space in cooperation with the pipe and in communication with some of said perforations, means for moving said space defining means with respect to said pipe, means for effecting the passage of liquid through the perforations traversed by said space, said means including cooperative piston and cylinder elements, one of said elements being movable with said space defining means, and the other of said elements being stationarily supported within the pipe. 20

22. In an apparatus for circulating liquid through perforations in well casing and the like, means defining a space in cooperation with the well casing, means for movably supporting said space defining means in said casing, and means disposed within the well casing outside of said space defining means for effecting the passage of liquid into said space and also through the perforations traversed thereby during the movement of said space defining means. 30

23. An apparatus for circulating liquid through perforations in well casing, embodying a pair of relatively movable sections, means for lowering said sections together to a predetermined zone within the well casing, means for stationarily supporting one of said sections, means for moving the other of said sections with respect to said first section, a pair of packers supported in fixed spaced relation for movement with said movably supported section, said packers forming a space in cooperation with the casing, a pressure creating means including cooperative piston and cylinder elements, said cylinder element being communicative with said space, and means for supporting one of said cooperative pressure creating elements for movement with the movably supported section, the other of said elements being supported by said stationarily supported section. 40

24. An apparatus for circulating liquid through perforations in well casing, embodying a pair of relatively movable sections, means for lowering said sections together to a predetermined zone within the well casing, means for stationarily supporting one of said sections, means for moving the other of said sections with respect to said first section, a pair of packers, means for supporting said packers in fixed spaced relation for movement with said movably supported section, said packers forming a space in cooperation with the casing, a pressure creating means including

cooperative piston and cylinder elements, said cylinder element being communicative with said space, means for supporting one of said cooperative pressure creating elements for movement with the movably supported section, the other of said elements being supported by said stationarily supported section, and means forming a passageway between said packers, and opening into the well casing outside of the space defined by said packers. 10

25. An apparatus for circulating liquid through perforations in well casing, embodying a pair of relatively movable sections, means for lowering said sections together to a predetermined zone within the well casing, means for stationarily supporting one of said sections, means for moving the other of said sections with respect to said first section, a pair of packers, means for supporting said packers in fixed spaced relation for movement with said movably supported section, 20 said packers forming a space in cooperation with the casing, a pressure creating means including cooperative piston and cylinder elements, said cylinder element being communicative with said space, means for supporting one of said cooperative pressure creating elements for movement with the movably supported section, the other of said elements being supported by said stationarily supported section, and means forming a 25 valve-controlled passageway between said packers, and opening into the well casing outside of the space defined by said packers. 30

26. An apparatus for circulating liquid through perforations in well casing, embodying a pair of relatively movable sections, means for lowering said sections together to a predetermined zone within the well casing, means for stationarily supporting one of said sections, means for moving the other of said sections with respect to said first section, a pair of packers, means for supporting said packers in fixed spaced relation for movement with said movably supported section, 40 said packers forming a space in cooperation with the casing, a pressure creating means including cooperative piston and cylinder elements, said cylinder element being communicative with said space, means for supporting one of said cooperative pressure creating elements for movement with the movably supported section, the other of said elements being supported by said stationarily supported section, means forming a passageway between said packers and opening into the well casing outside of the space and at opposite sides thereof, and a pair of valve structures disposed in said passageway at opposite sides of 50 the space defined by said packers. 55

27. An apparatus for cleaning perforations in well casing embodying, packing means defining a space in cooperation with the casing, means for movably supporting said packing means, means including a cooperative cylinder and piston operative within the well for effecting the passage* of liquid from the space through the perforations during the movement of the packing means, and means forming a passageway between said packers and opening into the well casing outside of 60 the space defined by said packers. 65

LANDES H. HAYWARD.
